UNITED STATES PATENT OFFICE

133,704

DESIGN FOR A BROOCH OR SIMILAR ARTICLE

Belmiro Pereira, Forest Hills, N. Y.

Application July 17, 1942, Serial No. 107,585

Term of patent 3½ years

To all whom it may concern:

Be it known that I, Belmiro Pereira, a citizen of the United States and resident of Forest Hills, New York city, in the county of Queens and State of New York, have invented a new, original, and ornamental Design for a Brooch or Similar Article, of which the following is a specification, reference being had to the accompanying drawing, forming a part thereof, and of which Figure 1 is a view in front elevation of a brooch or similar article showing my new design with the pin means shown in dot-dash lines; Fig. 2 is a side edge view thereof; Fig. 3 is a top view thereof; and Figs. 4, 5 and 6 are sectional views taken on lines 4—4, 5—5 and 6—6, respectively, of Fig. 1.

I claim:

The ornamental design for a brooch or similar article, substantially as shown and described.

BELMIRO PEREIRA.
